CARL F. SCHIPPEL, OF NEW YORK, N. Y., ASSIGNOR TO HERMAN W. HOOPS, OF NEW YORK, N. Y.

MARKER.

1,191,116.

Specification of Letters Patent. Patented July 11, 1916.

Application filed March 20, 1916. Serial No. 85,321.

To all whom it may concern:

Be it known that I, CARL F. SCHIPPEL, a citizen of the United States, and a resident of the city of New York, borough of Manhattan, in the county and State of New York, have invented a new and Improved Marker, of which the following is a full, clear, and exact description.

This invention relates to marking devices 10 and particularly to an improved arrangement for marking tennis courts or other places where a guiding line is desired, and has for an object the provision of an improved arrangement of vehicle and discharge members so that there will be a 15 discharge of the marking material in proportion to the speed of the vehicle.

Another object in view is to provide a marking device with a rotating brush opposite a discharge opening in a box which carries a granulated marking material, the arrangement being such that the brush will deposit a certain quantity over a given space which results in a discharge of material in 25 proportion to the speed of the movement of the device.

A still further object in view is to provide a discharge brush for marking devices and an agitating or stirring member for keeping the marking material in proper condition for being discharged.

In the accompanying drawings: Figure 1 is a side view of a device embodying the invention, certain parts being broken away 35 for better illustrating the construction. Fig. 2 is a front view of the structure shown in Fig. 1. Fig. 3 is a section through Fig. 1 on line 3—3, the same being on an enlarged scale. Fig. 4 is a sectional view through 40 Fig. 3 on line 4—4.

Referring to the accompanying drawing by numerals, 1 indicates a box or casing of any suitable material and also of substantially any suitable shape, though it is preferably the shape shown in Figs. 1 and 2 so that the marking material 2 may be readily fed to the discharge brush 3. The upper part of the casing 1 is provided with a lid 4 and also a handle bar construction 5 having 50 a suitable grip 6, which construction is shown with a pair of members engaging opposite sides of the casing 1 though other forms may be used without departing from the spirit of the invention. A rest or supporting leg 7 is hinged at 8 to the back of

the casing 1 so as to hold the device upright when not in use, but when in use the leg 7 is held folded against the back by a suitable catch or clamp 9.

The casing at the lower end is made from 60 wood and is provided with a separate end member 10 preferably of metal and shaped to conform to the construction of the brush, as more clearly shown in Fig. 4, so that the brush may contact therewith for almost half of its circumference. In addition, the front part of the casing is inclined at 11 so that all of the material in the casing may readily gravitate to the brush 3. The end member 10 is provided with a discharge opening 12 65 covered by a foraminous material 13 which may be perforated metal plate or may be a fine wire mesh, the arrangement being such that the bristles of the brush 3 will engage this foraminous member and force a certain quantity of the marking material 2 there-through, said marking material being of any suitable kind, as for instance, powdered plaster Paris or lime.

The brush 3 is rigidly secured to a shaft 80 14, which shaft also has rigidly secured thereto ratchet wheels 15 and 16, said ratchet wheels being adapted to receive the depending fingers 17 and 18 of spring 19, which spring is rigidly secured to the back 85 of the casing 1 by any suitable means, as for instance, screw 20 (Fig. 1). A bolt 21 extends through the spring at a short distance from the securing members 20 and is arranged to bring the spring under any 90 desired tension so that when the brush is rotated the spring will jar or shake the entire casing somewhat and will keep the material 2 in a proper state for entering the bristles of brush 3 so that some of the material may continually discharge through opening 12.

Shaft 14 extends through apertures 22 and 23 in the side walls of casing 1, said apertures being an appreciable size larger than the shaft so that the shaft may be adjusted for taking up any wear of the bristles, as it is preferable to have the bristles of the brush 3 engage the foraminous plate 13 continually. Bearing plates 24 and 25 support the shaft 14, these bearing plates being secured to the side walls of casing 1 by suitable screws or other fastening means passing through slots, as clearly shown in Fig. 3. When the bristles become somewhat worn 110

the securing means 26 are loosened and the plates together with shaft 14 and associated parts readjusted and then the securing means tightened. Adjacent the outer 5 ends of the shaft 14 slots 27 and 28 are provided into which the washers 29 and 30 fit, as shown more particularly in Figs. 1 and 3, said washers being secured to the traction wheels 31 and 32 in any suitable 10 manner, as for instance, by being screwed or bolted thereto.

Arranged in front of the discharge opening 12 and preferably centrally of the device, as shown more particularly in Fig. 2, 15 is a centering guide wheel 33 supported by a suitable axle 34 mounted in one or both of the side walls of the casing. This wheel is preferably arranged centrally but in front of the aperture 12 so that when using the 20 device for marking off a tennis court or other place a string or other guide may be readily followed and the marking material deposited in a straight line or curved line, as may be desired.

25 It is understood that the bottom edge of the casing 1 is maintained a short distance above the ground and that the traction wheels 31 and 32 provide the power for rotating the brush 3 and associated parts, thus 30 causing the brush to rotate at a speed in proportion to the forward travel of the device and, consequently, cause a discharge through opening 12 in proportion to the speed of the device. It will also be noted 35 that the discharge of the material is not through a pipe of ordinary discharge opening where a constant stream is allowed to pass by gravity, but is through an aperture and a certain quantity is continually fed 40 thereto by the bristles of the brush 3.

What I claim is:—

1. In a marker of the character described, a casing having a lower rounded end, said lower end having an aperture therein, a 45 foraminous covering plate for said aperture, a rotatable brush arranged in said lower end and adapted to contact with an appreciable portion thereof, said brush covering said foraminous plate and acting as a closure for 50 said aperture when not rotating, and traction means for rotating said brush whereby the marking material in the casing will be moved by the bristles of the brush to said foraminous plate and forced therethrough,

the amount of discharge being proportioned 55 to the speed of the device.

2. In a marker of the character described, a casing provided with a rounded lower end, a brush fitting said rounded end, said end having an opening covered by said brush, 60 traction members for rotating said brush for feeding part of the material from the casing through said opening, ratchet wheels connected to said brush, and a spring arranged in said casing engaging said ratchet 65 wheels for jarring and agitating the marking material so that the same will readily feed into the brush.

3. In a marker of the character described, a casing provided with a rounded lower end, 70 having an aperture therein, a foraminous plate covering said aperture, a brush fitting said rounded end and contacting with said foraminous plate for feeding marking material from the casing through said aperture, an axle connected with said brush and extending through the side walls of the casing, said side walls having apertures an 75 appreciable size larger than the axle so that the axle may be adjusted so as to move the 80 brush toward or from the foraminous plate in order to take up wear, journal plates connected to said side walls and engaging said axle for supporting the same in any adjusted position, and means connected to 85 said axle for rotating the same.

4. In a marker of the character described, a casing having an aperture in the lower end, a foraminous plate covering said aperture, a rotatable brush covering said foraminous plate and acting as a closure for said aperture when not rotating, and means for 90 rotating said brush.

5. In a marker of the character described, a casing having an aperture in the lower 95 end, a foraminous plate covering said aperture, a brush engaging said plate, means for rotating said brush, a ratchet wheel connected with said brush, and means operated by the ratchet wheel for agitating the marking material in the casing.

In testimony whereof I have signed my name to this specification in the presence of two subscribing witnesses.

CARL F. SCHIPPELL.
